BOBBIN TYPE STRING TOY

Henry Finkel, Montreal, Quebec, Canada, assignor to Twinpak Ltd., Lachine, Quebec, Canada

Filed May 7, 1969, Ser. No. 17,056

Term of patent 3½ years

Int. Cl. D21—02

U.S. Cl. D34—15

FIG. 1 is an elevation of the Diabolo top of my design;

FIG. 2 is an end elevation of the hand toy shown in FIG. 1;

FIG. 3 is a vertical cross section taken along the lines 3—3 of FIG. 1;

FIG. 4 is a partial cross section taken along the lines 4—4 of FIG. 2.

I claim:

The ornamental design for a bobbin type string toy, as shown.
